**BUFFING WHEEL AND METHOD OF
MAKING SAME**

John C. Wisnieski, Detroit, Mich., assignor to Lyon Incorporated, Detroit, Mich., a corporation of Delaware

Application January 22, 1954, Serial No. 405,560

8 Claims. (Cl. 51—193)

This invention relates to a method of making an abrading wheel and more particularly to a buffing wheel of the type having interlocked folded layers of cloth.

An object of this invention is to provide an economical time saving method of making a buffing wheel.

Another object of this invention is to provide a bias cut burlap buff wherein the outer periphery is defined substantially of end portions of folded open mesh burlap material.

A further object of this invention is to provide a burlap strip buff section having mesh like strands folded along the inner peripheral margin of the buff section and in a manner such as to minimize the sluffing off of the strands as a result of centrifugal forces existent during high speed operation.

A still further object of this invention is to provide the folded buffing section with a gripping supporting inner annular section such as to eliminate the necessity of stitching the buff fabric as is now commonly practiced in the art.

Another object of this invention is to provide a simple method by which the buff wheel may be dynamically balanced, and during continued use may maintain this balance.

In accordance with the general features of this invention there is provided in a method of forming a unitary buff including a multi-ply fabric outer annular section and a central circular supporting fabric gripping section, the steps of winding a strip of loosely woven burlap-like fabric flatwise upon itself and into generally tubular form around and in generally radially spaced relation to the supporting section, collapsing radially inward the generally medial area of the wound fabric tube toward and adjacent the periphery of the supporting section while holding the side portions of the tube toward and adjacent each other, establishing a preliminary gripping contact between the supporting section and the folded portions at the medial area to hold temporarily the folded portions together while removing the collapsing medium and thereafter contemporaneously securing the folded portions together and to the supporting section in unitary relation therewith.

Another feature of this invention relates to a tubular buff section comprising a fabric strip having at least its medial portion of loosely woven mesh so that the mesh thereof can become increasingly smaller toward the line of fold upon the contracting of the medial portion of the tube to a smaller diameter.

Still another feature of the invention relates to the provision of a novel supporting section for the aforesaid tubular buff section.

A further object of this invention is to provide a simple method of securing the central supporting section

2

to the bias cut folded burlap in such a manner as to eliminate the creation of any undesired pleats.

Other objects and features of this invention will more fully appear from the following detailed description taken in connection with the accompanying drawings which illustrate a single embodiment thereof, and in which:

Figure 1 is a plan view of a fabric sheet cut on the bias shown by parallel dotted lines and with one piece severed from the sheet;

Figure 2 is a plan view showing how the bias cut pieces of Figure 1 are sewn end to end to one another to form a continuous bias cut strip;

Figure 3 is a diagrammatic end view of an apparatus for practicing my invention showing a bias cut fabric strip being wound upon itself in tubular form about a supporting section disposed in the apparatus;

Figure 4 is an enlarged fragmentary cross-sectional view on the line IV—IV of Figure 3 showing diagrammatically by dotted lines how the wound tube is folded;

Figure 5 is a fragmentary cross-sectional view through the folded buff and supporting sections of Figure 4 showing their condition after removal from the apparatus in Figure 4 with the retaining prongs partially engaged in the fabric;

Figure 6 is a view similar to Figure 5 showing the prongs fully clenched substantially through the thickness of the fabric;

Figure 7 is a fragmentary side view of the structure shown in Figure 6 showing the central and radial air louvres in the central supporting section, and

Figure 8 is a fragmentary enlarged diagrammatic view showing the loosely woven mesh of the burlap fabric.

As shown on the drawings:

It will be appreciated from a study of the drawings that they are illustrative, in a diagrammatic way, of the step by step method in the fabrication and assembly of a buff wheel structure embodying the features of this invention.

Further, it will be noted that the details of the apparatus employed in the fabrication of the buff wheel have been generally omitted since any one of several different types of conventional apparatuses may be employed without departing from the novel scope of my invention herein disclosed and claimed.

The reference character 10 designates generally a continuous sheet of buff material such as is commonly used in buffing and polishing wheels at the present time. For illustration, this sheet can be made of a burlap material cut on the bias, as is conventional practice in the buff art, and which is illustrated in Figure 1 wherein the dotted lines 11 represent how the sheet 10 is to be cut into pieces 12.

After the sheet 10 has been cut into pieces 12, as is illustrated in Figure 1, the pieces are stitched end to end, as is illustrated at 13 of Figure 2, to form a continuous strip. It is well known in the buffing art that a bias cut stitched material has distinct advantages over a non-bias cut woof and warp material. Such bias cut type of buffing strip presents along the buffing surface a greater number of thread ends than in straight cut strips.

At this time, it might be well to note, as is customary in most conventional buff sections, that in addition to the fabric material or strip 12a, I propose to support the fabric ultimately on a relatively rigid central supporting section designated generally by the reference character 15. This section may be made of any suitably relatively

rigid material as compared with that of the fabric, such as metal, and shall be described more fully hereinafter.

The next step of my novel method requires the formation of the continuous bias cut strip 12a into a multi-ply tube or cylinder 16. Any number of plies may be wound into the tube 16 depending upon the number desired in the ultimate buff section to be formed from the tube.

Now, it is to be appreciated that numerous different ways will readily appear for forming the strip into such a tube but I have, for purposes of simplicity, illustrated diagrammatically, in Figures 3 and 4, a simple form of apparatus by which this forming of the fabric tube 16 may be accomplished. In Figures 3 and 4, the reference character 14—14 designates a pair of spaced circular oppositely facing mated arbors or drums of a diameter corresponding with the inner diameter of the fabric tube that is desired. These spaced arbors not only define together a drum on which the fabric strip 12a is helically wound, but, in addition, are so configurated on their confronting faces as to define a cavity 17 into which the medial portion of the multi-ply tube is subsequently adapted to be collapsed or constricted.

The radially inner portion of this cavity 17 is enlarged at 18 and constricted at 19 for a purpose to be now described.

Within the spirit and intent of this invention, it is contemplated that when the multi-ply wound fabric tube 16 is contracted, as by means of a drawstring 20, into the cavity 17, as shown by dotted lines in Figure 4, the fabric will be contemporaneously folded over and mounted on the periphery of the metal supporting disk 15. This disk 15 includes an annular portion 21 disposed in the recessed portions 19 of the arbors 14 and confronting staggered peripheral prongs 22 positioned in the enlarged cavity portions 18. Thus, it is clear that the mating faces of the opposed arbors 14—14 are so formed as to snugly receive and hold the metal supporting section on which the fabric buff section or tube 16 is to be folded and retained.

While likewise, for simplicity purposes, I have shown the constricting or collapsing means employed for folding the medial portion of the fabric tube 16 into the cavity 17 as being in the form of a drawstring, any other suitable means could be likewise used such, for illustration, as an "iris" type mechanism similar to that used with a camera lens. However, if a drawstring is used, it can optionally be left in or removed from the folded fabric as desired.

Referring to Figure 4, it will be clear that as the medial portion of the fabric tube 16 is progressively collapsed, as illustrated by dotted lines, into the cavity 17, it ultimately is received in the channel defined by the gripping means or prongs 22—22.

The prongs 22—22 are each of an angular shape and are alternately staggered with reference to the opposite prongs although they are all formed integral with the periphery of the annular portion 21 of the buff supporting section.

Subsequent to the complete folding of the medial portion of the multi-ply tube 16 with the drawstring 20 adjacent to the edge of portion 21 of the supporting member 15 (Figure 4), slight pressure may be exerted on the ends of the arbors 14 to move them toward each other and thereby force the sharpened tips of the prongs 22—22 into opposite sides of the folded fabric portion. In this manner, the gripping means or prongs may temporarily retain and hold the fabric tube in its folded position so that the arbors may thereafter be removed and, if so desired, the drawstring 20 may likewise then be removed.

In Figures 5 and 6, I have shown the condition of the buff and metal sections after their removal as a unit from the folding apparatus. In both illustrations, the drawstring 20 is shown as being disposed directly above the fold.

In Figure 5, the tips of the prongs 22—22 are illustrated as being in temporary gripping engagement with

the sides of the folded tube buff section 16. Any suitable means or press equipment may be employed for driving the prongs home from the position shown in Figure 5 to that illustrated in Figure 6 wherein the angular extremities of the prongs extend substantially clear through the thickness of the folded buff section 16. This results in a tight clinching of the prongs to the fabric and also compresses the folded layers of fabric tightly against each other.

10 It should be noted that in the operations illustrated in Figure 6, no stitching or adhesive is necessary for retaining the plies of the fabric tube section 16 together but if it is so desired the securement of the plies could be augmented by stitching or adhesive in the usual way.

15 In the foregoing manner, I have provided a novel method of not only folding the fabric section but of integralizing it with the periphery of the central metal supporting section 15. In Figure 7, I have shown a fragmentary side view of the integral unit of Figure 6 and have illustrated diagrammatically the open mesh comprising the fabric tube section 16. The central annular portion 21 of the metal supporting section 15 is apertured at 25 to receive the arbor or shaft of a buffing machine in a manner well known to those familiar with this art.

20 It will be appreciated that a series of these units may be used side by side on a single shaft as is conventional practice.

25 In addition, the annular metal portion 21 may also be provided with louvres or vanes 26 as are commonly used in the buffing art for ventilating and air circulating purposes in the cooling of the buff.

30 Before concluding, attention is directed to the fact that in the process of folding the medial portion of the fabric to a smaller diameter, the fabric would ordinarily have to become pleated if it were not for the open mesh of the same. By virtue of the use of an open mesh fabric, the mesh portions of the plies immediately adjacent the fold may become increasingly smaller toward the actual medial line so as to allow for the differences in the diameter of the material and thereby to preclude the formation of pleats.

35 While this latter feature is also old in the art, it is new here to so decrease the mesh as a part of moving it into the cavity where the reduced mesh portions may be contemporaneously flattened and clinched to the periphery of the central supporting section.

40 It further becomes apparent now that a very important feature and advantage of my invention resides in the use of the clinching prongs to define between them an annular channel about the periphery of the supporting section in which the folded medial portion of the multi-ply fabric strip is formed, compressed and contemporaneously secured to the supporting section.

45 While I have shown the fabric used as being of loosely woven mesh, it will be appreciated that, from the standpoint of accomplishing the foregoing advantageous features of my invention, only the longitudinal medial area of the strip, which is to be bent under, be made of loosely woven bias cut mesh. In other words, if it is so desired, the side edges of the strip could be made of a more closely woven fabric or muslin although it may be more economical to make the same strip of loosely woven material rather than to make one part of it from loosely woven material and the other part of closely woven material. In some instances, however, muslin or more closely woven fabric may be required for a particular buffing operation in which event the side edges of the fabric could be made of such material with only the medial area of loosely woven mesh.

50 It is also clear that the fabric, as is likewise old in the art, could be suitably impregnated with a buffing compound if it is so desired.

55 While I have illustrated and described my invention as an operation that may be entirely performed by hand,

it should be understood that such a method lends itself to the use of machines for large scale production.

It will be understood that modifications and variations may be effected without departing from the scope of the novel concepts of the present invention.

I claim as my invention:

1. In a method of forming a unitary buff including a multi-ply fabric outer annular section and a central circular supporting fabric gripping section, the steps of bias cutting a strip of loosely woven burlap-like fabric into a series of bias cut pieces, connecting each end of each bias cut piece to the end of another bias cut piece to form a continuous strip of bias cut material, winding said strip of loosely woven burlap-like fabric flatwise upon itself and into generally tubular form around and in generally radially spaced relation to a supporting section, collapsing radially inward the generally medial area of said wound fabric toward and adjacent the periphery of said supporting section while folding the side portions of the tube toward and adjacent each other, establishing a preliminary gripping contact between said supporting section and the folded portions at said medial area to hold temporarily the folded portions together, and thereafter contemporaneously securing the folded portions together and to said supporting section in unitary relationship therewith.

2. In a method of forming a unitary buff including a multi-ply fabric outer annular section and a central circular supporting section having integral flexible fabric gripping prongs, the steps of bias cutting a strip of loosely woven burlap-like fabric into a series of bias cut pieces, connecting each end of each bias cut piece to the end of another bias cut piece to form a continuous strip of bias cut material, winding said strip of loosely woven burlap-like fabric flatwise upon itself and into generally tubular form around and in generally radially spaced relation to a supporting section, collapsing radially inward the generally medial area of said wound fabric toward and adjacent the periphery of said supporting section while folding the side portions of the tube toward and adjacent each other, establishing a preliminary gripping contact between said supporting section and the folded portions at said medial area to hold temporarily the folded portions together and thereafter contemporaneously securing the folded portions together and to said supporting section in unitary relationship therewith.

3. In a method of forming a unitary buff including a multi-ply fabric outer annular section and a central circular supporting fabric gripping section, the steps of bias cutting a strip of loosely woven burlap-like fabric into a series of bias cut pieces, connecting each end of each bias cut piece to the end of another bias cut piece to form a continuous strip of bias cut material, winding said strip of loosely woven burlap-like fabric flatwise upon itself and into generally tubular form around and in generally radially spaced relation to a supporting section, collapsing radially inward the generally medial area of said wound fabric toward and adjacent the periphery of said supporting section by contracting a draw-string wound around said medial area while folding the side portions of the tube toward and adjacent each other, establishing a preliminary gripping contact between said supporting section and the folded portions at said medial area to hold temporarily the folded portions together and thereafter contemporaneously securing the folded portions together and to said supporting section in unitary relationship therewith.

4. In a method of forming a unitary buff including a multi-ply fabric outer annular section and a central circular supporting fabric section with annularly arranged gripping means defining a peripheral channel for receiving the fabric section, the steps of bias cutting a strip of loosely woven burlap-like fabric into a series of bias cut pieces, connecting each end of each bias cut piece to the end of another bias cut piece to form a continuous strip

of bias cut material, winding said strip of loosely woven burlap-like fabric flatwise upon itself and into generally tubular form around and in generally radially spaced relation to a supporting section, collapsing radially inward the generally medial area of said wound fabric tube toward and into the channel of said supporting section while folding the side portions of the tube toward and adjacent each other, establishing a preliminary gripping contact between said channeled gripping supporting section and the folded portions at said medial area to hold temporarily the folded portions together and thereafter contemporaneously securing the folded portions together within and to said annularly gripping supporting section in unitary relationship therewith.

5. In a method of forming a unitary buff including a multi-ply fabric outer annular section and a central circular supporting fabric gripping section, the steps of bias cutting a strip of loosely woven burlap-like fabric into a series of bias cut pieces, connecting each end of each bias cut piece to the end of another bias cut piece to form a continuous strip of bias cut material, winding said strip of loosely woven burlap-like fabric flatwise upon itself and into generally tubular form around and in generally radially spaced relation to a supporting section, constricting radially inward the generally medial area of said wound fabric tube toward and adjacent the periphery of said supporting section while folding the side portions of the tube toward and adjacent each other, establishing a preliminary gripping contact between said supporting section and the folded portion at said medial area to hold temporarily the folded portions together and thereafter contemporaneously securing the folded portions together and to said supporting sections in unitary relation therewith, said fabric strip having at least its medial portion of loosely woven fabric so that the mesh thereof becomes increasingly smaller toward the line of fold upon the constricting of the medial portion of the tube to a smaller diameter about the supporting section.

6. A unitary buff comprising a multi-ply fabric outer annular section comprising a flat strip of loosely woven burlap fabric wound in tubular form upon itself and folded along a medial line with the mesh of the fabric increasingly smaller toward the line of fold and with the side edges of the strip defining the periphery of the fabric section and a radially inner supporting and relatively rigid section having circumferentially spaced air louvers disposed generally inside said fold and having peripheral and staggered radial prongs on opposite sides of the folded fabric section and embedded in and extending substantially through the thickness of the folded section, said prongs defining substantially an annular channel in which the folded portions of said fabric section adjacent said medial line are formed, compressed and retained on said supporting section, said section comprising a single circular unitary plate with the prongs alternately bent in opposite directions from and integral with its outer periphery, said prongs including an axial portion extending generally axially from said rigid section and terminating in a generally radial leg the extremity of which is angled over said axial portion biting into said fabric section at an inclined angle thereby facilitating assembly.

7. In a buff section including a buff ring and a supporting ring encompassing its inner periphery, said supporting ring comprising a rigid annulus with a radially extending portion having its outer periphery margin provided with a plurality of spaced radial slits defining oppositely angled radial buff ring gripping extensions, each of said extensions including a portion extending generally axially from said radial portion and terminating in a generally radial leg the extremity of which is angled over said axial portion biting into the material of the buff ring at its inner margin at an inclined angle to facilitate assembly of said rings.

8. In a method of forming a unitary buff including a multi-ply fabric outer annular section and a central circular supporting fabric gripping section, the steps of bias

cutting a strip of loosely woven burlap-like fabric into a series of bias cut pieces, connecting each end of each bias cut piece to the end of another bias cut piece to form a continuous strip of bias cut material, winding said strip of loosely woven burlap-like fabric flatwise upon itself and into generally tubular form around and in generally radially spaced relation to a supporting section, collapsing radially inward the generally medial area of said wound fabric toward and adjacent the periphery of said supporting section while folding the side portions of the tube toward and adjacent each other, temporarily engaging said portions adjacent said supporting section to hold them temporarily in folded relation, and thereafter contempor-

aneously securing the folded portions together and to said supporting section in unitary relationship therewith.
